UNITED STATES PATENT OFFICE.

WILLIAM G. LIEBIG, OF DETROIT, MICHIGAN.

BORING-MACHINE FOR BRUSH-BACKS.

1,125,351.

Specification of Letters Patent.

Patented Jan. 19, 1915.

Application filed February 9, 1912. Serial No. 676,657.

To all whom it may concern:

Be it known that I, WILLIAM G. LIEBIG, who am a citizen of the United States, residing at Detroit, in the county of Wayne and State of Michigan, have invented certain new and useful Improvements in Boring-Machines for Brush-Backs, of which the following is a specification.

This invention relates to machines for 10 boring holes in wooden blanks used for brush backs, and has for its object an improved device adapted especially for use with rounded brush backs used for carpet sweeper brushes and the like, in which 15 several rows of holes are to be bored in predetermined order.

In the drawings:—Figure 1 is a perspective of the assembled device. Fig. 2 is an elevation of the back of the machine. Fig. 3 20 is an elevational view of the left end of the machine, as viewed from the front. Fig. 4 is a plan view of the master roller and of the blank whose boring is desired, at about the level of the line $y-y$ of Fig. 2. 25 Fig. 5 is a side elevational view of the reciprocating slide carrying the actuating hook which engages the master roll, to rotate it about its axis. Fig. 6 is a plan view of this slide, partly in section.

30 Projecting from the base 1 of the machine is a bracket 2, which supports a traveling table 3, from each end of which rise struts 4, through which engage adjusting and holding screws 5 and 6 for the master roll 7 35 and the wooden blank 8 respectively. Within or on one face of one or both of the struts are rotatably mounted a series of intermeshing gear wheels 9, by which rotative movement of the master roll 7 is communicated to the blank 8. The upper portion of the base is bent over so as to overhang the table 3 and its supported parts, and in it is 40 rotatably journaled the spindle 11 of the chuck 12, in whose lower end is removably held the auger 13. Rotative actuation is 45 communicated thereto by means of the belt 14, (see particularly Fig. 3) which passes over the pulley 15 on the upper end of the stem 11, and which is preferably protected 50 by the shield 16. The belt 14 passes over the pulley 18^a, which is keyed to the shaft 19 on which is mounted the pulley 18, to which actuation is communicated from the engine by means of the belt 17; for the sake 55 of compactness and efficiency of operation, the belt 14 is preferably led over the idler

pulley 20 between the pulley 15 and the pulley 18^a.

The horizontal operating shaft 21, which extends across the rear of the machine at 60 about the level of the table 3, has mounted on it the fly wheel 22, over which the belt 17^b passes to communicate actuation thereto, and also the cams or eccentric disks 23 and 24. Of these the cam 23 has on one face the 65 wrist pin 25, over which engages the knuckled end 26 of the link 27, which is pivoted to the rear end of the lever 28, by which the gimlet carriage or boring member 12 is depressed to effect the boring of 70 holes in the wooden blank. By suitable proportioning of the length of the lever and of the diameter of the cam and the rotative speed of the actuating power belt, the desired frequency and degree of throw or descent of the gimlet can be secured. The cam 24 has running over its periphery the 75 roller 29 which is journaled in the end of the lever 30, which is pivoted at 31 to the upper part of the frame of the machine, so 80 that its short arm 32 extends downward in a nearly vertical position to the level of the horizontally reciprocating bar 33, which is preferably mounted on the upper end of the pivoted link 34, whose lower end is 85 pivoted to the bracket 34^a which projects from the frame or base of the machine. This short arm 32 being rigid in its angular position with respect to the lever 30, and consequently swinging therewith, moves to 90 and fro as the lever 30 rises and falls, thereby moving the slide 33 forward and back for the purpose now to be described. The forward part of this bar 33 is partly cut away, as shown particularly in Figs. 5 and 95 6, to accommodate the rear end of the bar 35 which is pivoted therein, as at 36 in such a way as to be capable of a limited swing in a horizontal plane in a manner and for reasons hereinafter explained; it is kept 100 normally in alinement with the larger bar 33 by means of the leaf spring 37. Pivoted to the forward end of this bar 35 is the rear end of a hook 38, whose point engages over the studs or knobs 40 on the master roll 7, 105 and which is yieldingly held thereupon by the leaf spring 41 which presses upon its top. The possible tendency of the hook 38 to rise too high as it rotates the master roll in its rearward travel, is counteracted and 110 regulated by means of the stop bracket 47 which depends from the bent-over upper

portion 10 of the frame or base, its height being regulated by the nut 48. This bracket preferably carries on its lower end a roller 49, which directly engages the hook 38. By the rotation of the cam 24, by which the lever 30 and its connected and coöperating parts are actuated, the actuation of the master roll 7 through an arc of desired size is accomplished at each cycle of operations of the device. This is brought about through the medium of the hook 38, which is pivoted to the lower forward end of the short arm 32.

Farther along on the shaft 21 from the cam member referred to, that is, toward the right hand end of the machine is supported on the sleeve 45 a cam 50, on one face of which is located a wing 51, and on the other face of which is located a projecting ratchet 52 which is adapted to be engaged by the hooked lower point of a branch or bracket 53 which is attached to the lever member 30, in such a way that each time the lever 32 and with it the branch or bracket 53 swings because of the raising of the lever 30, the cam member 50 is rotated through an arc whose size is determined by the number of teeth which peripherally constitute the ratchet 52; for example, if there are eight teeth in the ratchet, the cam member 50 is, at each actuation, moved through a 45 degree angle. The number of ratchet teeth in each case corresponds with the number of rows of pins or studs in the master roll 7 at any circumferential point, and correspondingly with the number of holes to be complementarily bored in the wooden blank 8. When, through the repeated actuation of the master roll 7 rotatively, as already described, the boring of one set of holes has been completed, the cam member 50 has, by the corresponding repeated pulls upon its ratchet portion 52, been so rotated that its wing piece 51 engages the head 54 of the pivoted lever 55, whose forward end carries a spring pressed pawl 56, which engages in the serrated edge 57 of the rear side of the table 3, pushing it to the right to a degree sufficient to throw the next row of studs or knobs 40 on the master roll 7 under the hook 38. The boring of the next circumferential row of holes is then proceeded with in like manner, and at the end of that period the completion of another rotation by cam 50 again throws the pivoted lever 55 and moves the table 3 one more notch in its travel toward the right of the machine. When the last row or girdle of holes has been bored through the reaching of the correspondingly located set of studs 40 by the hook 38, the right hand end of the table 3 has been projected so far to the right by the repeated actuations of the lever 55 that the next actuation in this manner forces the right hand end of the table against the bent-over or

forwardly-inclined finger 59 of the lever 58, which is pivoted at 60 in position to swing horizontally when thus engaged by the table end. This lever when in its normal and un-actuated position, as shown in full lines on Fig. 4, engages with its heel 61 over the top of the rod 62, which may be slightly beveled, in such a way as to hold it down against the upward pull of the spring 63; when, however, this lever 58 is thus tripped, the pull of the spring 63 shoots the rod 62 upward; this being connected with the link 64, whose upper end is connected with the control lever 65 of the clutch member by which the fly wheel 22 is operatively connected with the shaft 21. This stops the further action of the roller and blank-actuating parts, and forces upon the attention of the operator the fact that the boring of the holes in that particular blank has been completed, and that a new blank must be inserted between the holding screws 5, and the table 3 again moved to its initial starting position at the extreme left of its path of travel, when the clutch 65 being again thrown to operative position, the alternate raising and lowering of the link 27 through the rotation of the cam 23 is begun once more, in turn actuating the parts already described. The return of the lever 58 to its interfering position, as regards its inclined finger 59, across the extreme end of the path of travel of the table 3, is effected by a pull of the operator's hand, after the table has been moved to its starting position at the left side of the machine.

The adjustable support 43 which rises from the forward edge of the table 3 engages under the center portion of the blank 8, just clearing its surface as it rotates, thereby preventing it from bending to any extent or possibly breaking when being pressed upon by the operation of the boring member.

The arrangement of parts hereinabove described can be used under varying conditions and to meet special needs with slight modification without departing from the spirit of my invention; for example the arrangement of actuating belts and pulleys may be varied somewhat, or changed in whole or in part to intermeshing gear wheels, levers and the like; and for the disclosed mounting of the cam member 50 of the rotating shaft 21 which contemplates the employment of a sleeve 45 to avoid to the utmost the influence of the rapidly rotating shaft upon the slowly rotating cam member 50 an independent bracket with suitable bearings, projecting from the supporting frame may be substituted.

What I claim is:

1. In a boring machine, in combination with a frame member, a power shaft journaled therein, a plurality of power-trans-

mitting members operatively connected therewith and with the several parts whose timed actuation is sought, a table member 5 slidably supported in position for limited travel across said frame member, said table being provided with means for rotatably supporting a blank and with a rotatable master roll operatively connected with said blank-supporting means and adapted to be 10 positively engaged by one of said power-transmitting members to effect its rotation and consequently the rotation of the blank through an arc of predetermined size, a reciprocatory boring member, means to project it into engagement with the blank between successive rotative actuations thereof, a table-actuating member operated upon at the completion of a predetermined number of rotative movements of the blank, where- 15 by the table is moved lengthwise to the desired degree, and a stop member adapted to be tripped by engagement by said table at the limit of its lengthwise travel, and releasing means controlling the further operation 20 of the several power-transmitting members.

2. In a boring machine, in combination with a traveling table provided with means for rotatably supporting a rounded blank 30 inserted therein, a master roll operatively connected with said blank-supporting portion of the table, means for rotating said master roll and thereby said blank through a predetermined arc at each operation, a reciprocatory boring member, means for actuating the same against the blank, means for imparting a lengthwise movement to said table and thereby to said master roll and said blank after a predetermined number of 35 rotative actuations, and means controlled from a common source of power whereby the several parts are actuated in desired sequence, substantially as described.

3. In a boring machine, in combination 45 with a supporting frame member, a table capable of limited horizontal travel with respect thereto, said table being provided with means for rotatably supporting a blank and with means for communicating rotative ac- 50 tuation thereto, a reciprocatory member for engaging said blank-actuating means on said table to cause the intermittent rotation of the blank, a longitudinally movable boring member adapted to engage the blank be- 55 tween successive rotative actuations thereof, a common power shaft with which said reciprocatory member and said boring member are operatively connected, means rendered active by the completion of a pre- 60 determined number of rotative actuations of the blank whereby the supporting table and with it the blank are moved in a direction parallel with the axis of the blank, a spring-actuated stop member, and a pivoted lever 65 member adapted to normally hold said stop

member in inoperative position and to be swung to releasing position by the engagement thereagainst of said table in one of its lengthwise movements, thereby permitting the stop member to terminate the further operation of the machine, substantially as described. 70

4. In a boring machine, the combination of a power shaft, a reciprocatory boring member operatively connected therewith, a traveling table adapted to rotatably support a blank in position to be intermittently engaged by said boring member, a reciprocatory member operatively connected with said power shaft, adapted to transmit actuation to said blank-supporting portion of the table between successive operations of said boring member, means rendered active by the completion of a predetermined number of actuations of said blank, whereby the table and its supported blank are moved lengthwise of the axis thereof, a pivoted lever member adapted to be swung from its normal position by the engagement of the table thereagainst upon the completion of its lengthwise path of travel, and a spring-actuated stop member adapted to be released by the swing of said pivoted lever member, whereby the further operation of the machine is terminated, substantially as 95 described. 90

5. In a boring machine, in combination with a power shaft, a series of cam members carried thereby, a series of link and lever members, each deriving its actuation from some one of said cam members, a reciprocatory boring member adapted to be actuated through the medium of one set of said link and lever members, a traveling table for rotatably supporting a blank in 100 position to be engaged by said boring member, the blank being adapted to be rotated through a predetermined arc between each forward movement of the boring member by the action of certain other of said link 110 and lever members, and the table and its supported blank being adapted to be moved lengthwise, after a predetermined number of rotative actuations of the blank, by the action of still other of said link and lever members, a pivoted lever member adapted to be displaced by the engagement of said table thereagainst at the end of its path of lengthwise travel, and a spring-actuated stop member normally held in inactive position by said pivoted lever member and adapted to be released by the displacement thereof by said table, thereby terminating the further operation of the machine. 115 120

6. In combination with a frame member, a reciprocatory boring member supported therein, a traveling table provided with means for rotatably supporting a blank and with a master roll operatively connected therewith, a reciprocatory master-roll actu- 125 130

ating member whereby it and thereby the blank are rotatively actuated to the degree required between successive operations of said boring member, a power shaft with which the several enumerated parts are operatively connected for action in desired sequence, automatic means for moving said table lengthwise of the axis of the blank after the completion of a predetermined number of rotative actuations thereof, a pivoted trip lever adapted to be engaged by said table upon the attainment of the end of its lengthwise path of travel, and a spring-actuated stop member adapted to be released by the displacement of said trip member, thereby terminating the further operation of the machine, substantially as described.

7. In combination with a power shaft, a plurality of power-transmitting members operatively connected therewith, a reciprocatory boring member adapted to be actuated by certain of said power-transmitting members, a traveling table adapted to rotatably support a blank, a reciprocatory actuating member whereby the intermittent rotation of the blank through an arc of predetermined size is effected, means brought into action by the completion of a predetermined number of rotative actuations of the blank whereby the supporting table is moved lengthwise, a pivoted lever member adapted to be displaced from its normal position by the engagement of said traveling table thereagainst upon reaching the end of its path of possible lengthwise travel, and a stop member yieldingly held in inoper-

ative position by said pivoted lever member when the same is in normal position, adapted to cause the stoppage of the machine when released by the displacement of said pivoted lever member, substantially as described.

8. In a boring machine, in combination with a supporting frame, a boring member slidably mounted therein, a traveling table carrying a master roll and means for rotatably supporting a blank in operative relation therewith, a common power shaft, means for transmitting actuation therefrom to said boring member, an oscillatory hook member deriving its actuation from said power shaft, adapted to peripherally engage said master roll and rotate the same through an arc of predetermined size, and thereby to said blank from said common power shaft, means actuated by the movement of said master-roll actuating means whereby said table and thereby its supported parts is periodically actuated longitudinally of said master-roll and said blank after a predetermined number of rotative operations thereof, and means adapted to be actuated by the engagement thereagainst of said table when it reaches the end of its intended path of travel, whereby the further operation of all of said parts is automatically stopped, substantially as described.

In testimony whereof I affix my signature in presence of two witnesses.

WILLIAM G. LIEBIG.
